UNITED STATES PATENT OFFICE.

GEOERGE HENRY WHEARY, OF RACINE, WISCONSIN.

AUTOMATIC LOCKING MEANS FOR TRUNKS.

1,198,387.

Specification of Letters Patent. Patented Sept. 12, 1916.

Application filed July 19, 1916. Serial No. 110,024.

To all whom it may concern:

Be it known that I, GEORGE HENRY WHEARY, a citizen of the United States, and resident of Racine, in the county of Racine and State of Wisconsin, have invented new and useful Improvements in Automatic Locking Means for Trunks, of which the following is a description, reference being had to the accompanying drawings, which 10 are a part of this specification.

This invention relates to improvements in automatic locking means for trunks more particularly adapted for use in connection with wardrobe trunks formed in two sections and having a top cover and a plurality of locking bolts.

In wardrobe and other trunks which are divided medially, vertically to form a wardrobe section and a body or drawer section, the wardrobe section is usually provided with a top or upper end cover for convenience in removing garments from said wardrobe section. In trunks of this type a plurality of locking devices is usually provided for locking the sections and the cover in closed position. The independent operation of these locking devices is not convenient and requires considerable time and is otherwise objectionable.

It is one of the objects of the present invention to overcome the before mentioned objectionable features and provide a trunk with a plurality of locks which may be unlocked by a keyed engagement with one of the locks.

A further object of the invention is to provide an automatic locking means adapted to lock trunk sections and a trunk top cover at a plurality of points, one of the locking members being constructed and arranged to automatically unlock the parts which are locked thereby when the other locked parts are unlocked and swung to open position.

A further object of the invention is to provide an automatic locking means for trunks which will permit the locking of two portions of the trunk together while a third part of the trunk remains in open position.

A further object of the invention is to provide a locking member which is normally in locked position and is temporarily moved to unlocked position while the cover is being swung to open position.

A further object of the invention is to provide an automatic locking means for

trunks which is of simple construction, is strong and durable and which is well adapted for the purpose described.

With the above and other objects in view, 60 the invention consists of the improved automatic locking means for trunks and its parts, and combinations as set forth in the claims and all equivalents thereof.

In the accompanying drawings in which 65 the same reference characters indicate the same parts in all of the views: Figure 1 is a front view of a trunk provided with the improved automatic locking means; Fig. 2 is a rear view of the trunk with the wardrobe section thereof shown in section to show the locking mechanism within the said section, the top cover of said wardrobe section indicated by dotted lines as in open position; Fig. 3 is a vertical sectional detail view on a larger scale of the upper portion of the trunk; Fig. 4 is a similar view with the top cover of the wardrobe section shown partly in open position, the top cover also being indicated in another position by 80 dotted lines; Fig. 5 is a vertical sectional detail view thereof taken on line 5—5 of Fig. 3; Fig. 6 is a detail sectional view of a modified form of locking means with the top cover of the wardrobe section shown in 85 closed position; Fig. 7 is a similar view with the top cover shown in open position; and Fig. 8 is a detail sectional view of the lock used in both forms.

Referring to the drawings the numeral 8 90 indicates a trunk body which is divided vertically to form a body portion 9, a wardrobe section 10, the wardrobe section being open at its upper end and provided with a top cover 11 which is hinged to the forward 95 edge of the body portion. The top cover 11 is locked to the wardrobe section by a hasp lock 12 which is controlled by a key 13 in the ordinary manner while the wardrobe section is locked to the body portion by an 100 automatic lock 14 controlled by the movement of the top cover 11. The automatic lock 14 comprises the hinged hasp member 15 attached to the body portion of the trunk and the bolt member 16 attached to the 105 wardrobe section thereof. The hasp member 15 is of ordinary construction and is provided with the usual eyed projection 17 which is adapted to extend through the opening 18 of the bolt member 16 and to be 110 entered by the slideable bolt 19 forming part of the bolt member 16. The rectangular bolt

19 is slidably mounted within the casing 16' of the bolt member 16 and is provided with a stem 20 which extends upwardly through the casing and is connected by a short chain 21 to the lower end of an actuating rod or bar 22 slidably mounted on the inner side of one of the walls of the wardrobe section. A coiled spring 23 surrounding the bolt stem and interposed between the bolt and the casing serves to normally and yieldingly hold the bolt in locking position. A transverse pin 24 projecting from the bolt and extending through a slot 24' in the casing limits the downward movement of the bolt.

15 The lower end portion 19' of the bolt 19 is beveled and likewise the upper forward edge 17' of the eyed projection 17 to provide for the automatic engagement of said parts when the hasp member is pushed inwardly 20 to locking position. A flat spring 25 automatically swings the hasp member outwardly when released by the bolt.

The actuating rod or member 22 slidably extends through guide brackets 26 and terminates at a point adjacent the upper edge portion of the wardrobe section and its upper end portion 22' is bent at right angles to provide for the automatic or manual upward pull of said member.

30 A rod actuating hook member 27 loosely, pivotally connected to a bracket 28 mounted on the inner face of the top cover 11 is positioned to hook under the bent portion 22' of the actuating rod 22 and pull said rod upwardly to unlock the hasp lock 14 when the top trunk cover is swung to open position.

The hook member engages the outer edge portion 29 of the actuating rod and is provided with a shouldered portion 30 adjacent 40 the pivotal connection of the hook member with the bracket 28. This shouldered portion is so positioned with relation to the hook portion of the member that when the top cover of the trunk is swung almost to 45 vertical position the said shouldered portion will strike against the bottom portion of the bracket and limit further independent movement of the hook member and it will then swing upwardly with the top cover and disengage the bent or shouldered portion of 50 the actuating rod as indicated by dotted lines in Fig. 4. When thus disengaged the actuating rod will be pulled downwardly by gravity and the bolt spring 23 and the bolt 55 will be in position to engage the hasp member 15 when it is pushed to closed position.

A stop pin 31 projecting from the actuating rod engages one of the guide brackets 26 and limits the downward movement of the said 60 rod and maintains it in position to be engaged by the hook member 27.

In the modified form shown in Figs. 6 and 7 an angular hook member 27' is provided which hooks beneath the opposite edge 65 portion of the bent part 22' of the actuating

bar 22 and pulls said bar to open position. The trunk sections are now swung apart so that the bent portion of the actuating bar will snap off the hook portion 32 of the said bar 27' and the said bar will drop to its 70 normal position as shown in Fig. 6.

In order to permit the hook member to again engage the bar when the top cover is swung to closed position the lower end portion of the hook member is curved laterally 75 as indicated by the numeral 33 so that it will be deflected sidewise in moving downwardly and thus assume its normal position shown in Fig. 6. The pivotal connection 34 between the hook member and the bracket is 80 sufficiently loose to permit this side play.

From the foregoing description it will be seen that the automatic locking means for trunks is of very simple construction and is well adapted for the purpose described. 85

What I claim as my invention is:

1. The combination of a trunk having a plurality of connected together elements, of an automatic locking means therefor, consisting of a locking member for two of the 90 elements controlled by the movement of a third element, said locking means also operable to lock or unlock the two elements together while the third element is in open position. 95

2. The combination of a trunk having a plurality of hinged together elements, of an automatic locking means therefor, comprising a manually actuated locking member locking two of the elements together, and an automatic locking member locking a third element to one of the locked together elements, the second mentioned locking member being unlocked by the movement of one of the first mentioned locked together elements toward its open position, said construction permitting the locking of the said second mentioned locking member while one of the first mentioned elements is in open position. 100

3. The combination of a trunk having a plurality of hinged together elements, of an automatic locking means therefor, comprising a manually actuated locking member locking two of the elements together, and an automatic locking member locking a third element to one of the locked together elements, the second mentioned locking member momentarily moving to unlocking position while the first mentioned elements are moved 110 to open position. 115

4. An automatic locking means for a trunk having a plurality of hinged together elements, comprising a hasp member, a bolt member positioned to engage the hasp member, means yieldingly holding the bolt member in locked position, and means for momentarily moving the bolt member to unlocking position controlled by a movement of one of the hinged together elements, said 120 125 130

construction permitting the locking of the hasp member to the bolt member while one of the first mentioned elements is in open position.

5. An automatic means for a trunk having a plurality of hinged together elements, comprising a hasp member yieldingly held in open position, a bolt member positioned to engage the hasp member, means for yieldingly holding the bolt member in locked position, and other means for momentarily moving the bolt member to unlocked position while one of the hinged elements is moved to open position, said construction permitting the locking of the hasp member to the bolt member while one of the first mentioned elements is in open position.
10. An automatic locking means, comprising a hasp member, a bolt member positioned to engage the hasp member, an actuating member connected to the bolt member, and a hook member engaging the actuating member for momentarily moving the bolt member to unlocked position.
15. An automatic locking means, comprising a hasp member, a bolt member positioned to engage the hasp member, means for yieldingly holding the bolt member in a locking position, an actuating member connected to the bolt member and having an angular portion, and a hook member engaging the angular portion of the actuating member for momentarily moving the bolt member to unlocked position, said hook member having a 45
20. shoulder portion which co-acts to disengage the hook member from the angular portion after the bolt member has been moved to unlocked position.
25. An automatic locking means, comprising a hasp member, a bolt member posi-

tioned to engage the hasp member, means for yieldingly holding the bolt member in a locking position, an actuating member connected to the bolt member, and a hook member engaging the actuating member for momentarily moving the bolt member to unlocked position and when moved to unlocked position to disengage and permit the bolt member to move to locking position.

30. 8. An automatic locking means, comprising a hasp member, a bolt member positioned to engage the hasp member, means for yieldingly holding the bolt member in a locking position, an actuating member connected to the bolt member and having an angular portion, and a hook member engaging the angular portion of the actuating member for momentarily moving the bolt member to unlocked position, said hook member having a 40

35. shoulder portion which co-acts to disengage the hook member from the angular portion after the bolt member has been moved to unlocked position.

In testimony whereof I affix my signature. 50

GEORGE HENRY WHEARY.
